FREDERICK F. MONROE, SR., FREDERICK F. MONROE, JR., AND HENRY E. SMITH, OF
DETROIT, MICHIGAN.

AUTOMOBILE-SIGNAL.

1,279,401.

Specification of Letters Patent. Patented Sept. 17, 1918.

Application filed January 19, 1914. Serial No. 812,980.

To all whom it may concern:

Be it known that we, FREDERICK F. MONROE, Sr., FREDERICK F. MONROE, Jr., and HENRY E. SMITH, citizens of the United States, residing at Detroit, county of Wayne, State of Michigan, have invented a certain new and useful Improvement in Automobile-Signals, and declare the following to be a full, clear, and exact description of the same, such as will enable others skilled in the art to which it pertains to make and use the same, reference being had to the accompanying drawings, which form a part of this specification.

This invention relates to automobile signals, and its object is simple, efficient and comparatively inexpensive apparatus by means of which the driver of an automobile may indicate following traffic the intended movement thereof.

A further object is a device of the character stated that is equally useful in the day time or at night.

A further object is a signal device having the function of a tail-light as well as that of a signaling device. The novel features of construction by which these and other objects of the invention may be attained are shown in the accompanying drawings in which—

Figure 1 shows a device embodying our invention mounted upon the fender at the rear end of an automobile.

Fig. 2 is a side view thereof.

Fig. 3 is an enlarged vertical section of the device showing the structural arrangement of the parts.

Fig. 4 is a section taken through the center of the signal arm and the apertured barrel upon which it is mounted.

Similar characters refer to similar parts throughout the drawings and specification.

The device consists of a barrel 1, mounted in the brackets 2, 2, in a manner to prevent rotation thereof. The brackets are provided with a base 3 to support the device in any convenient position as upon the rear end of a fender as shown in Figs. 1 and 2 or in other positions at the rear of the vehicle, as may be convenient or desirable. One end of the barrel 1 is provided with a glass shield 4 preferably in the form of a lens, and the device is so set on the vehicle that this lens covered opening is continuously exposed to view to one looking at the rear of the vehicle.

Mounted within the barrel is an electric lamp 5, supported therein by means of a threaded portion 6 engaging in the end of the barrel. The lamp may be supplied with electric current from any convenient source controlled by a switch of any approved type. The barrel is provided with the apertures 7 and 8 upon each side thereof, shown more particularly in Fig. 4. The signal arm 9 is mounted for rotation on the barrel 1, one end of the arm being hollow and the opposite end being provided with a counter-weight 10, which tends to hold the signal in an upright position as shown in full lines in Fig. 2. The outer end of the arm is provided with an opening covered with a lens 11, and as shown in Fig. 4, the bearing of the arm on the barrel 1 is of such form that when the arm is in the upright position the apertures 7 and 8 are covered. The bearing does not extend completely about the barrel 1, there being a space or opening provided between the cylindrical bearing and the open hollow portion of the arm, and when the arm is drawn to the right as shown in Fig. 4, at right angles to its normal position, this opening between the hollow part of the arm and the bearing registers with the opening 7 in the barrel allowing light from the lamp 5 to illuminate the interior of the arm and the lens 11, which may be of colored glass and thus apprise the operator of a following vehicle of the intended movement of the vehicle bearing the signal. The signal may also be turned to the left in like manner and the opening 8 be brought into registration with the opening leading into the hollow arm and indicating a turn of the vehicle to the left. In the daytime the lamp 5 need not be lighted as the movement of the signaling arm is a sufficient indication but at night it becomes desirable to use a light as the signaling arm itself might not be distinguished.

As shown in Fig. 3 the signaling arm is provided with a hub 12 about which are wound the operating cords 13, as shown in Figs. 1, and 2. There should be two cords and these may conveniently pass beneath the signaling device about the pulleys 14, thence about the pulleys 15, and forward to near the operator's seat where they are connected respectively at an equal distance above and below a pivot point of the operating lever 16. Movement of the lever in one direction

rotates the signal in one direction, and reverse movement of the lever reverses the direction of rotation. The method of operating the cords, however, is immaterial as 5 they may be operated in any convenient manner and the lever 16 is here shown to indicate one method of operation.

As shown in Fig. 3, the barrel 1 may be apertured at 20, upon the lower side adjacent the lens through which light will be 10 projected on the license tag 21, which may be conveniently supported on one of the brackets 2.

Having thus briefly described our invention, 15 what we claim and desire to secure by Letters Patent of the United States is—

In an automobile signal, a hollow cylindrical case having a lens at one end, the opposite end being threaded, an electric 20 lamp within the casing having a support adapted for threaded engagement with said threaded end, said case having apertures upon opposite sides thereof, a hollow signal-

ing arm having a counter-weight integrally formed therewith, said arm being mounted 25 for rotation on the case and normally adapted to cover both the said apertures therein, said arm having a lens covered opening near the outer end, means for rotating the arm in either direction on the case 30 to indicate the intended movement of the vehicle, a bracket attached to the casing in a manner to prevent rotation thereof and adapted to support the device on a vehicle, said casing also having an aperture in the 35 lower side thereof adapted to illuminate an inscription carried by the bracket.

In testimony whereof, we sign this specification in the presence of two witnesses.

FREDERICK F. MONROE, SR.
FREDERICK F. MONROE, JR.
HENRY E. SMITH.
